UNITED STATES PATENT OFFICE.

JEROME BLUM, OF PELHAM, NEW YORK.

GAME APPARATUS.

Application filed April 5, 1926. Serial No. 99,858.

This invention relates to games and has particular reference to a game apparatus particularly designed to simulate the game of hockey.

5 One of the principal objects of the invention is to provide a game apparatus which affords means for the playing of a highly amusing and attractive game which embodies in well-balanced proportions the elements of skill and luck.

The invention further comprehends a game apparatus which admits of the playing of a game closely simulating the game of hockey, which comprises a combination and 15 arrangement of elements designed to contain the hazards and barriers ordinarily imposed in the game which it simulates.

As a still further object the invention contemplates a game apparatus which is 20 comparatively simple in its construction and inexpensive to manufacture.

With the above recited and other objects in view, reference is had to the following specification and accompanying drawings in 25 which there is exhibited one example or embodiment of the invention which is in no way intended as a limitation upon the scope of the appended claims as it is to be clearly understood that variations and modifications 30 which properly fall within the scope of said claims may be resorted to when found expedient.

In the drawings—

Figure 1 is a perspective view of the game 35 board;

Fig. 2 is a similar view of one of the sticks used in connection therewith, and

Fig. 3 is a view of the playing element.

Referring to the drawings by characters 40 of reference the game board includes a bottom wall or base 10 which may be of any desired configuration although the same is preferably rectangular as illustrated. The base or bottom wall 10 is provided with a 45 marginal upstanding wall 11 formed at diametrically opposite points with openings 12 and 13 simulating the goals in a hockey game. The upper surface of the bottom wall which defines a playing field, is sub- 50 divided by upstanding barriers 14 equidistantly spaced from the goals 12 and 13, and spaced from each other to provide an intermediate playing compartment 16 and an outer playing compartment 17, said compartments having communication with each other 55 by a plurality of passageways 18 formed in

the barrier walls 14. Disposed centrally of the intermediate compartment 16 is a starting point or tee 19 upon which the playing element 20 is initially placed. Each 60 player in the game is provided with a stick or driving element 21, which preferably is in the nature of a straight rod.

Where the game is played by two players, each is provided with a stick or club 21 and 65 takes up a position on opposite sides of the game board. With the playing element arranged at the starting point or tee 19, at a given signal each player attempts to drive the ball toward the opponent's goal opening, 70 first by causing the same to pass through one of the passageways 18 of the barrier wall. The player succeeding in driving the playing instrument 20 through the passageway in the opponent's barrier wall, must then 75 drive the same through the goal opening. The opponent may endeavor to return the playing element back through the barrier wall to the center compartment and thence through the opponent's barrier wall to the 80 opposite outer compartment. The barrier walls act in the nature of the defense in the game of hockey, and it will be found that in addition to this barrier, the opponent may 85 employ his stick or club to prevent the ball or playing element 20 from being driven through the goal opening.

What is claimed is:

1. A game apparatus, including a movable playing piece, driving elements therefor, a 90 game board including a bottom wall, an upstanding marginal wall having diametrically disposed goal openings, transverse barrier walls having passageways therein equidistantly spaced from the goals and spaced from each other sub-dividing the playing field into distinct playing compartments, and a starting point intermediate the game board upon which the playing piece 95 is initially placed.

2. A game apparatus simulating the game 100 of hockey, including a movable playing piece, driving elements therefor, a game board consisting of a bottom wall presenting an upper playing surface, marginal side 105 and end walls projecting upwardly from the game board, the end walls having goal openings therein, a starting point intermediate the game board, and transverse upstanding walls extending between the side walls and having passageways thereon.

JEROME BLUM.
